UNITED STATES PATENT OFFICE.

NILS HERMAN CEDARQUIST, OF ALHAMBRA, CALIFORNIA.

PHONOGRAPH-CABINET.

1,359,791.

Specification of Letters Patent. Patented Nov. 23, 1920.

Application filed November 3, 1919. Serial No. 335,322.

To all whom it may concern:

Be it known that I, NILS HERMAN CEDARQUIST, a citizen of the United States, residing at Alhambra, in the county of Los Angeles and State of California, have invented new and useful Improvements in Phonograph-Cabinets, of which the following is a specification.

This invention relates to a phonograph cabinet having an inclosed horn or amplifier, and pertains particularly to the amplifier structure.

Phonograph cabinets of the so-called "cabinet type" are commonly constructed with a box divided into two compartments. The upper one is open at the top and disposed therein is a phonograph motor mechanism. The lower compartment has a horn or amplifier built in, and is connected to the reproducer or sound box by a tone arm. It is common practice to build up the amplifier of wood or metal. Wood amplifiers have certain disadvantages due to the inherent quality of such material in absorbing vibration. Metal, on the other hand, has natural periods of vibration which accentuate certain tones and destroy the natural quality of the sound. It is the primary object of my invention to provide an amplifier which does not absorb or accentuate vibration. Another object of this invention is to provide an amplifier of the character described with a wall which serves to direct air vibration and acts as a sounding board, whereby the amplifier may be built of wood. A further object of this invention is to provide a wall of the character described which has its greatest amplitude of vibration adjacent the mouth of the horn.

In addition to the broader features of this invention, there are certain details of construction, whereby a simple, compact, easily assembled and disassembled structure is obtained.

These objects will be more fully understood, as will also other objects and corresponding accomplishments of my invention from the following detailed description of a preferred embodiment thereof. For the purpose of this description, reference is had to the accompanying drawing, in which:

Figure 1 is a front elevation of a phonograph cabinet with a portion in section showing the amplifier; Fig. 2 is an enlarged section taken on the line 2-2 of Fig. 1

showing the amplifier; and Fig. 3 is a perspective view of the sounding board.

Referring more particularly to Fig. 1 the cabinet proper is indicated by A. The phonograph motor mechanism is indicated generally by B, and the amplifier by C. A wall or partition extends across the cabinet dividing the latter into a chamber D in which records and other accessories may be stored, and an amplifier chamber E.

Disposed in the amplifier chamber E and extending thereacross at an angle is the sounding board base 5. The base is cut with a recess 6 on the upper side to accommodate the motor mechanism 7 of the phonograph machine, the latter being indicated by dotted lines in Figs. 1 and 2. The base may be attached by a screw extending through an opening 8 and engaged with the bottom of the cabinet. A mortise or groove 9 is provided upon the face of the base board to receive one end of the sounding board 10, the other end being disposed in a recess 11. Secured to the sounding board and base board by any suitable means is a block 12 which closes the space between the sounding board and the partition 4. The face of the block 12 is inclined from top to bottom.

The sounding board 10 is preferably of spruce. It is sprung into place when dry, and serves as one wall of the amplifier. At the forward end of the sounding board are a number of holes 13, which increase the resiliency of the board at its point of attachment to the base board and allow a greater amplitude of vibration at the mouth. The walls 4 and 10, the latter being a sounding board, provide a flaring chamber.

Mounted upon the top of the base board 5 is a board 14, which closes the amplifying chamber and serves as a support for the phonograph machine B. The tone arm 15 of the phonograph communicates with the amplifier at the rear end thereof and adjacent the block 12. In order to permit free vibration of the sounding board, the top edge and the bottom edge are cut away from a point adjacent the back to the front so that the sounding board does not come in contact with either the board 14 or the bottom of the cabinet, except at the rear thereof. In order to close the spaces at the top and bottom edges, felt strips 16 and 17 are secured to the sounding board, thereby preventing the direct passage of air vibrations to the

rear thereof. The front of the cabinet is provided with openings 18 extending across the face thereof, some of these serving to permit the passage of sound waves, while 5 the remaining ones, although having no function, enhance the ornamental appearance of the cabinet.

The position of the handle for winding the machine and other parts for the control 10 of its speed, as well as receptacles for needles and other accessories may be provided, as desired. These, however, form no part of my invention and are not shown or described in detail. One wall of the amplifier is 15 formed by a sounding board, which may be detachably secured in the cabinet.

What I claim is:

1. In a phonograph cabinet having a box-like chamber, a sounding board anchored at 20 the back and front edges, the other edges being free and undamped, said board extending across said chamber to define an amplifier horn tube.

2. In a phonograph cabinet having a box-like chamber, a sounding board extending across said chamber to define an amplifier horn, said board having the greatest resiliency adjacent the mouth end of said horn.

3. In a phonograph cabinet having a box-like chamber, a sounding board anchored at 30 the back and front edges, the other edges being free and undamped, said board extending across said chamber to form a wall of an amplifier horn, said board having the greatest resiliency adjacent the mouth of said horn.

4. In a phonograph cabinet having a box-like chamber, a base board extending across 40 said chamber, and a sounding board on said base board supported under tension between the ends thereof to form a side of the amplifier horn, the other edges thereof free and undamped.

5. In a phonograph cabinet having a box-like chamber, a base board extending across 45 said chamber, and a sounding board on said base board supported under tension between the ends thereof to form a side of the amplifier horn, said sounding board having its greatest resiliency at the mouth end of said horn.

6. In a phonograph cabinet having a box-like chamber, a base board extending across 55 said chamber, and a sounding board on said base board supported under tension between the ends thereof to form a side of the amplifier horn, said sounding board having a portion of the material thereof cut away at the

forward end to provide greatest resiliency at the mouth of said horn.

7. In a phonograph cabinet having a box-like chamber, a base board extending across 60 said chamber, and a sounding board on said base board supported under tension between the ends thereof to form a side of an amplifier horn, said sounding board having perforations at its forward end to increase the amplitude of vibration thereof.

8. In a phonograph cabinet having a box-like chamber, a base board extending across 65 said chamber, a sounding board on said base board supported under tension between the ends thereof to form a side of an amplifier horn, and a phonograph board adapted to support the phonograph motor mechanism 70 disposed above said sounding board, said sounding board being spaced away at its bottom edge from the bottom wall of said chamber and spaced away at the top edge from said phonograph board so as to be free 75 to vibrate.

9. In a phonograph cabinet having a box-like chamber, a base board extending across 80 said chamber, a sounding board on said base board supported under tension between the ends thereof to form a side of an amplifier horn, a phonograph board adapted to support the phonograph motor mechanism 85 disposed above said sounding board, said sounding board being spaced away at its bottom edge from the top wall of said chamber and spaced away at the top edge from 90 said phonograph board so as to be free to vibrate, said sounding board having its greatest resiliency to vibration at its forward end adjacent the mouth of said horn.

10. In a phonograph cabinet having a box-like chamber, a base board extending across 95 said chamber, a sounding board on said base board supported under tension between the ends thereof to form a side of an amplifier horn, and a phonograph board adapted to support the phonograph motor mechanism 100 disposed above said sounding board, said sounding board being spaced away at its bottom edge from the bottom wall of said chamber and spaced away at the top edge from 105 said phonograph board so as to be free to vibrate, said sounding board being perforated at its forward end 110 to increase the amplitude of its vibration.

In witness that I claim the foregoing I have hereunto subscribed my name this 28th day of October, 1919.

NILS HERMAN CEDARQUIST.
